UNITED STATES PATENT OFFICE

CARL G. OLSON, OF CHICAGO, ILLINOIS, ASSIGNOR TO SHAKEPROOF LOCK WASHER COMPANY, INCORPORATED, OF CHICAGO, ILLINOIS, A CORPORATION OF DELAWARE

MECHANISM FOR FORMING LOCK WASHERS

Application filed November 17, 1927. Serial No. 233,749.

This invention relates to dies for punching certain articles of characteristic shape from sheet metal and pertains more particularly to a novel arrangement of progressive dies for the rapid production, from stock strips, of lock washers of the so-called rolling tooth type, commonly known in the market as shakeproof lock washers and described in United States Patent No. 1,419,564, issued to

10 Richard T. Hosking June 13, 1922.

The claimed novelty in this invention is found in a new arrangement of a plurality of progressive dies, by which a certain "method of producing pronged washers", set forth in 15 the patent issued to J. R. Richer, February 14, 1928, No. 1,659,161, carried out on a basis of rapid production. The method, as described in that patent, is a method of procedure whereby two different types of rolling tooth 20 washers are produced from the same stock strip, one having external and the other internal prongs. The procedure comprises punching a hole in the strip, stamping out a blank concentric with the hole and having a 25 serrated edge forming regular prongs or teeth around its periphery, and twisting the external prongs thus formed out of the plane of the blank, and finally twisting the internal prongs out of the plane of the strip and 30 stamping out a second concentric blank with a circular periphery.

The novel mechanical means by which the aforesaid method is practiced comprises an arrangement and combination of progressive 35 dies by which internal toothed washers and external toothed washers are rapidly and cheaply produced from the same stock strip.

Another novel feature of improvement is in the structure of certain of the dies whereby 40 the teeth of both washers are respectively twisted about their longitudinal axes while they are still integral parts of the original stock strip, or in other words, before they are completely severed therefrom.

45 The progressive dies described herein may be characterized as a new combination of die elements, mostly old in themselves, but co-operating to produce the new and useful results of the method of procedure above designated.

With the foregoing and certain other objects in view, which will appear later in the specifications, my invention comprises the devices herein described and claimed and the equivalents thereof.

55

In the drawings Fig. 1 is a plan view of a stock strip, showing its appearance after each successive operation of the dies.

Fig. 2 is a part sectional diagrammatic view of the progressively arranged dies, the stock 60 strip and the feeding rolls.

Fig. 3 is a vertical section through the dies constituting the right-hand half of the series shown in Fig. 2.

Fig. 4 is a detail of the external toothed 65 washer.

Fig. 5 is a sectional detail of one rib of the punch and two ribs of the die for twisting the teeth of the external toothed washer and at the same operation severing the washer 70 from the stock strip.

Fig. 6 is a detail of the internal toothed washer.

As is clearly shown in the drawings, my progressive die arrangement and mode of operation is a combination of certain punching and forming elements. Together they constitute the claimed means by which I produce from the same stock strip washers, one having 75 external and the other having complementary 80 internal, axially twisted teeth.

The strip 1 is propelled by suitable strip- 85 feeding means, as rollers 2, 3, 4, in the usual way.

The die mechanism as a whole is of the well-known progressive type having individual dies or punches spaced apart, each adapted to perform a separate operation on the washer.

In the manufacture of these washers on a 90 large production commercial scale I prefer to divide the progressive dies into two groups, one group of dies making the external and the other making the internal toothed washers. I do this merely for the sake of structural 95 simplicity and facility of repair to the dies, but for the purpose of this description I have shown and will describe them as being combined in a continuous assembly.

However the progressive die is arranged, 100

whether in a single structure as shown in Fig. 2, or divided into two groups as above noted, the external type washer is the one first produced and the internal type of washer is the second.

The stock strip, as will be seen in the drawings, is wide enough, and the spacings are far enough apart to provide material from which pronged washers of the desired size can be 10 punched.

Punches 5, 6 and dies 5a, 6a for simultaneously piercing and piloting the strip, are provided, as is usual in progressive dies of this character, and 7 is a blanking punch, externally ribbed or fluted lengthwise and adapted 15 with its die 7a to blank a washer 1a and push it part way through the strip without severing it entirely.

A second punch 8 having longitudinal ribs 20 with beveled work-engaging faces 9 pushes the partly severed washer 1a completely through the stock strip and simultaneously twists the teeth 10 or prongs of the washer out of the plane of the blank. The means 25 employed for twisting these prongs is illustrated in detail in Fig. 5. The spaces X for the washer prongs 10 between adjacent internal ribs 11 of the die members 8a, are narrower than those in the preceding blanking 30 die 7a and in consequence the beveled faces 9 twist the prongs 10 while the washer is being pushed between the ribs 11 of the die 8a and severed from strip 1.

There is now stamped out a blank, concentric with the first pierced hole, having a serrated edge forming regular twisted teeth 35 around its periphery.

Punch 8 is the distance of two successive 40 equal steps of advancement of the stock strip away from the punch 7 in order to provide room for the dies 7a and 8a.

After leaving die 8 the stock strip, deprived of its external toothed washer, Fig. 4, passes on to the next operation, which is the 45 removal of a concentric internal toothed washer.

If desired, the stock strip 1 at this stage 50 may be coiled, to be later fed into the internal toothed dies shown at the right-hand side in Fig. 1 and in section in Fig. 3. In any case, however, a die 12 is provided to twist out of the plane of the strip 1 the internal teeth 13 left in the stock after it has passed the group 55 of dies that formed the external toothed washers. It will be noted that the twisting of the internal teeth 13 occurs while the teeth are as yet integral parts of the stock strip.

Die 12 is provided with longitudinal ribs, the ends of which comprise a serrated series 60 of forming faces 14.

In two moves of the stock strip the newly 65 twisted teeth arrive at a punch and die 15 which is adapted to flatten the washer, as indicated by the dotted circle, Fig. 1.

The flattened stock strip is next operated

on by a blanking punch and die 17 that severs the internal washer, Fig. 6, thus completing the manufacture from the same stock strip of two different types of washers, one having external and the other internal twisted teeth.

By the means above described I have produced a mechanism for rapidly operating the method as stated, namely, punching three concentric openings in the strip, the smaller having a circular periphery, the intermediate having a serrated periphery forming a series of regular prongs or teeth and the largest having a circular periphery, thus cutting blanks, one having external, and the other having complementary internal teeth, and twisting the teeth of both washers while said teeth still remain integral with the stock strip.

Having thus described my invention, what I claim and desire to secure by Letters Patent is:

1. Means for producing two different kinds of pronged lock washers from the same stock strip, comprising strip-feeding means, dies for progressively piercing and piloting the strip, a ribbed punch and a complementary ribbed die adapted to blank one of said washers and to push it part way only through the strip, a second ribbed punch and a ribbed die having beveled work-engaging faces on its ribs adapted to push said washer completely through the stock and to simultaneously twist its prongs, the spaces for the prongs between adjacent ribs in said last mentioned die being narrower than those in the said blanking die, a pilot, a tooth-twisting punch and die adapted to twist the prongs remaining in the stock strip after passing the above mentioned dies, a die for flattening the area of the annular ring of material surrounding the said last mentioned prongs and a blanking punch and die for severing said flattened ring from the stock strip, thereby producing a second washer.

2. A means for producing pronged lock washers from stock strip comprising strip feeding means, dies for progressively piercing and piloting the strip, a co-operating ribbed punch and ribbed die adapted to blank a washer and to push it part way only through the strip, a second ribbed punch having beveled work-engaging faces on its ribs adapted to push said washer completely through the stock and a ribbed die co-operating therewith to simultaneously twist the prongs of the washer, the spaces between the ribs of said last mentioned die being narrower than the corresponding spaces of said ribbed blanking die, thereby producing one complete lock washer and preparing the stock strip for simultaneously yielding other complementary washers.

In testimony whereof, I affix my signature.

CARL G. OLSON.
